UNITED STATES PATENT OFFICE.

PAUL S. HAUTON, OF ELIZABETH, NEW JERSEY, ASSIGNOR TO THE HAUTON CORPORATION, A CORPORATION OF DELAWARE.

CALENDAR.

Application filed August 23, 1919, Serial No. 319,384. Renewed November 15, 1921. Serial No. 515,427.

To all whom it may concern:

Be it known that I, PAUL S. HAUTON, a citizen of the United States, and a resident of Elizabeth, in the county of Union and 5 State of New Jersey, have invented a new and useful Calendar, of which the following is a full, clear, and exact description:

This invention relates to calendars and particularly to a calendar to be used on the 10 end of a fountain pen, pencil, or the like, and has for an object the provision of a construction which is simple and which is provided with a minimum number of parts, while at the same time presenting a perfectly clear and intelligent arrangement so 15 that any desired date may be quickly and easily ascertained.

Another object in view is to provide a calendar for fountain pens and the like of the 20 kind commonly known as perpetual calendars and at the same time present an easily operated construction which is completely out of the way when the pen or pencil is being used.

25 A further object of the invention is to provide a calendar on the cap of a fountain pen in such a manner as not to interfere with the usual use of the pen or cap while at the same time providing a sliding sleeve for one 30 form of indication and a rotating sleeve for another form of indication.

In the accompanying drawing:

Figure 1 shows a fountain pen with the cap at the rear end, said cap having a calendar thereon disclosing the invention.

Figure 2 is a longitudinal sectional view through the cap shown in Figure 1, the same being on line 2-2 of Figure 1, and on an enlarged scale.

40 Figure 3 is a view similar to Figure 2 except the same is taken on the line 3-3 of Figure 1.

Figure 4 is a transverse sectional view through Figure 1 on line 4-4.

45 Figure 5 is an elevation of what may be termed the day sleeve.

Figure 6 is a plan view showing a development of the day sleeve illustrated in Figure 5.

50 Figure 7 is an exterior view of the cap with a series of numbers and grooves forming certain features of the invention.

Figure 8 is a development of a protecting sleeve shown in Figure 9.

55 Figure 9 is an elevation of the protecting

sleeve adapted to fit over the cap shown in Figure 7.

Figure 10 is a development of the sleeve shown in Figure 7.

Referring to the accompanying drawing 60 by numerals, 1 indicates a fountain pen of any desired kind provided with a cap 2, which interiorly is of the same general shape as the caps now on the market, except preferably the end is cut off and threaded exteriorly so as to receive the auxiliary cap 3 for holding the protecting sleeve 4 in place. The cap 2 is provided with an enlarged knurled head 5 for engagement, and with an annular shoulder 6 on which one end of the sleeve 4 65 is rotatably mounted, the opposite end being rotatably mounted on the exterior surface of the interiorly threaded sleeve or auxiliary cap 3 (Figure 3). This arrangement permits an easy rotation of the sleeve 4 while the 70 ends are supported. A chamber 7 is provided by the particular arrangement of the sleeve 4 and associate parts, and in this chamber a sleeve 8 is mounted, said sleeve being provided with a number of numerals 80 9 thereon whereby it may be termed a day sleeve, as these numbers indicate the days of the months. As shown in Figure 6 these numbers are arranged in a particular arbitrary manner so as to correctly indicate 85 the days of the week when the calendar is properly set, and not only indicate the proper days of the week in any year, but indicate on what day of the week the first 90 of the month will be found. This sleeve is provided with an opening 10 having a roughened thumb member 11 arranged adjacent thereto and a numeral or legend 12 95 arranged on the opposite side, the numeral in the drawing being 19, but it, of course, may be any other numeral desired. In use numeral 19, shown at 12 in Figure 6 is associated, for instance, with numeral 19 on the periphery of the cap 2 so as to indicate the year 1919. The sleeve 8 is provided with a 100 notch 13 so that as the sleeve is reciprocated, as hereinafter fully described, it will not close or come beneath the opening or notch 14. The sleeve 8 is also provided with a 105 cut out portion presenting a spring structure 15, which is preferably bent down slightly so as to extend into one of the annular grooves 16 in the cap 2. The grooves 16 are the same distance apart as the groups of 110 numbers 17 on the chart 18 formed or

mounted on the surface of the cap 2. This chart is provided with a column or line 19 indicating the days of the month and the number of days in the particular month, 5 while directly opposite and in line therewith is found a plurality of lines of groups of numbers 17 coacting with the number "19" in Figure 6. These numbers are positioned in the proper relationship to always indicate 10 the proper number for any given year on any particular day by the numerals 9 on sleeve 8. The protecting sleeve 4, as shown in Figure 8, is provided with apertures 14, 20 and 21, with legends 22 indicating the days of the 15 week, and the word "days" at 23 opposite the opening 14 so that when the numbers are arranged as shown in Figure 1 they will read "January 31" and the word "days," which indicates that January has thirty one 20 days, while at the same time the set of numbers 9 is automatically arranged to show that January 31, 1919 falls on Friday, and that the first of January 1919 falls on Wednesday. When the sleeve 8 is moved 25 over so that the "19" thereon will come opposite a number through opening 10 on the chart 18 which represents 19 the numbers 9 will indicate the correct numbers for the month of January and their correct arrangement 30 in the week as shown in Figure 1. The thumb member 11 is intended to project preferably a very short distance through the slot 20 so as to be readily grasped by the thumb or finger whereby the sleeve 8 may be 35 slid along until the proper number on cap 2 will come opposite opening 10. Before this is done the desired month is found first, for instance January and then the sleeve 8 is slid along until a proper number appears 40 opposite opening 10 whereupon the calendar is properly set for the month of January 1919, for instance. The groups of numbers 17 as illustrated in Figures 7 and 10 indicate an arrangement which will extend over 45 a period of seven years, after which a new group must be provided, though the arrangement of numerals 9 may remain the same, and also all the other parts may remain the same.

50 To assemble the device the auxiliary cap is unscrewed after which the sleeve 4 may be slid off, and as it moves off it will carry with it the sleeve 8. By depressing the thumb member 10 somewhat and exerting pressure on the end of said sleeve 8 said sleeve will move out of sleeve 4 whereupon all the parts are in a separated condition. To assemble the device a reverse action is carried out.

55 As the sleeve 8 moves along during the ordinary operation of the calendar the turned down end of spring 15 will snap into the respective grooves 16 for, in a limited sense, locking the sleeve in any adjusted position.

60 If the parts were arranged as shown in Fig-

ure 1, and the thumb member 11 was pushed toward the point of the pen, namely to the left as far as possible, the "19" on the sleeve 8 would be moved to the end of the slot 20 and the numeral "22" would be exposed 70 through the opening 10, which would indicate the month of January 1922. This "22" will be seen at the lower left hand corner of the series of numbers 17 shown in Figure 10 and is in the horizontal column opposite December because the notch or window 20 is offset a distance equal to the space from one series of numbers 17 to the next series. In addition to indicating the year 1922 it would indicate that the first of January in that 80 year will fall on Sunday. If the thumb member 11 was moved to the opposite extreme position, namely to the end of slot 20 nearest the auxiliary cap 3, the numeral "21" would appear so that with the number 85 "19" it would mean the year 1921 and January 1st in this year would be Saturday.

It would be observed that the entire calendar including cap 2 is formed of four separate pieces, namely the cap, the sleeve 4, 90 sleeve 5, and auxiliary cap 3. It will also be noted that the protecting sleeve 4 is provided with windows 14, 20 and 21, but if desired instead of having cut out openings as illustrated in the drawing, the sleeve 4 95 could be made of transparent material and colored except for these windows. Also other modifications and changes could be made without departing from the spirit of the invention.

Whenever it is desired to have numerals indicating a calendar for any given month sleeve 4 is rotated around the cap 2 until the desired month is secured, as for instance January, after which the thumb member 11 105 is pushed until the sleeve 8 has been shifted so that the correct year will be disclosed through opening 10, as for instance "19" which added to the "19" on the sleeve 8 will give the year 1919. When this has been 110 done the days of the month and the series of numbers 9 will be properly positioned beneath the various weekly designations 22 so that the calendar for January 1919 is ready for examination, the same as shown 115 in Figure 1. The same method is carried out for any month in any year for seven years, said seven years being illustrated on the drawing as 19 to 25 inclusive, though any other set of seven years could be substituted, and it is intended to substitute other years whenever desired.

From the foregoing description taken in connection with the accompanying drawing, the advantages of the construction and 125 method of operation will be readily understood by those skilled in the art to which the invention appertains, and while I have described the principle of operation together with the apparatus, which I now consider 130

to be the best embodiment thereof, I desire to have it understood that the apparatus shown is merely illustrative and that such changes may be made when desired as are within the scope of the appended claims.

What I claim is:

1. A calendar of the character described comprising a tubular cap having a column of twelve designations thereon indicating the months of the year with two figures indicating the number of days in the month, and a plurality of arbitrary series of numbers indicating the last two figures of any year, a sleeve fitted over said tubular cap having a series of numbers arranged in thirteen vertical columns so that any seven columns thereof will indicate the days of a month arranged in the order of the days of the week, and a number indicating the first two numbers of the year, said sleeve being formed with an opening adjacent said last mentioned number whereby when the said opening is positioned over any one of the series of arbitrary numbers on the cap 25 it will be read with the number adjacent the opening on the sleeve for indicating the year.

2. A calendar comprising a tubular member, an outer sleeve rotatably mounted on the tubular member, an inner sleeve slidably mounted in said outer sleeve and rotatable therewith, said outer sleeve having a year window, a month window, and a day window indicating the days of the month 35 and week, said outer sleeve also provided with weekly designations adjacent said day window, and tables of numbers on said inner sleeve, some of said numbers appearing through one of said windows simultaneously with the appearance of the month through a second window and the days of the month through said day window.

3. A calendar of the perpetual type comprising a base member having a cylindrical periphery provided with a number of legends indicating the months of the year, a series of numbers arranged in lines, the numbers being in pairs, a sleeve slidably and rotatably mounted on said base member, said sleeve being formed with a window through which any pair of said series of numbers may be seen when the sleeve has been properly moved, said sleeve also having a year number adjacent said window and a set of numbers indicating the days of the months, and a protecting sleeve rotatably and telescopically fitted over said first mentioned sleeve and base member, said protecting sleeve being formed with a window for exposing said month legends individually, a second window for indicating the year number on said first mentioned sleeve and the year number of said series appearing in the window of the first mentioned sleeve, and a third window 65 for exposing the numbers indicating the days

of the month, said protecting sleeve being provided with designations indicating the days of the weeks, said designations being arranged along one edge of the third window, and said protecting sleeve being also provided with designations reading "days", said designations being arranged adjacent the month window.

4. A calendar of the perpetual type comprising a cylindrical base member, a sliding and rotating sleeve telescoped upon said base member, a protecting sleeve rotatably fitted on said base members and over said first mentioned sleeve, said protecting sleeve having a month window, a year window and a day window, and means on the base member and the first mentioned sleeve for indicating the year, month and day through the respective window within a predetermined period of several years, legends indicating the different years, months and days being brought opposite the respective windows by an adjustment of said first mentioned sleeve and said protecting sleeve.

5. A calendar for fountain pens, pencils and the like comprising a series of year numbers on the pen or pencil, a list of the months in the year, each month being opposite the last two numbers of seven years, said numbers being one line of said series of numbers, a sliding and rotatable sleeve member positioned over said series of numbers, said sleeve member being formed with a window adapted to disclose any of said year numbers, a number adjacent said window consisting of the first two numbers of a year number to be read with any two numbers disclosed through the window in said sleeve member, a series of day numbers on said sleeve member indicating the days of the month, said day numbers being arranged in six horizontal lines and thirteen vertical columns, and a protecting sleeve fitting over said sleeve member having a window adapted to frame a sufficient quantity of said day numbers to indicate all the days of a given month regardless of the position of the sleeve member in respect to the framing window.

6. A calendar for fountain pens, pencils and the like comprising a series of year numbers arranged in longitudinal and circumferential columns on the cylindrical part of the pen or pencil, a list of names opposite the longitudinal columns indicating all of the months in a year, each month being opposite a longitudinal column containing pairs of numbers indicating the last two numbers of several years, a rotatable and sliding sleeve member telescopically fitting over the sleeve carrying said series of year numbers, said sleeve member being formed with a window adapted to be brought opposite any pair of year numbers so as to disclose the same, said sleeve members being formed with a pair of year numbers opposite the window.

which is to be read with the year number shown through the window, and with a series of day numbers arranged in longitudinal and circumferential columns at a distance from 5 said window, and a protecting sleeve telescopically fitting over the first mentioned sleeve and the body carrying the series of year numbers, said protecting sleeve having a window for disclosing one month's designations at a time, a second window for disclosing the year designations on the sleeve member and the year number adjacent on the body member, and a framing window for said day numbers on said sleeve member, and 10 legends arranged adjacent the framing window for indicating the days of the week, and legends formed adjacent to the month window.

7. A calendar of the character described comprising an inner tubular member, a sleeve capable of reciprocation and rotation arranged on said tubular member, and an outer tubular member rotatably mounted on said inner tubular member and said sleeve, 25 said outer tubular member having three windows, one for indicating the month, one the year and one the days of the month and week, said sleeve having indications thereon presenting the days of the week for any month and the two first numbers of the year, and a window adjacent said year number, said inner tubular member having indications thereon representing the months of a year with the number of days in the 30 particular month along side, and a series of numbers indicating the last two numbers of a year, said last two numbers being adapted to be seen through the window in said sleeve, the particular position of the window determining the numbers disclosed, said numbers co-acting with the year number on said sleeve.

8. A calendar comprising an inner member, having a circle of legends indicating 45 the months of the year, a second series of circles indicating the last two numbers of different years, a reciprocating and rotating sleeve mounted on top of said inner member, said sleeve having a window and 50 notch and a table of numbers arranged so that any seven lines thereof will indicate the days of the week of a given month, said sleeve being provided with a year number having two figures arranged at the left of said window, and an outer sleeve having a window for disclosing seven lines of said table of numbers, means including the days of the week arranged in a line on said sleeve and acting as a heading to the number disclosed through said window, a second window in said outer sleeve for disclosing one month of the year, and a third window for disclosing the year number on said first 55 mentioned sleeve and one of the year numbers mentioned on said reciprocating sleeve.

9. In a calendar, a table of numbers thereon, said table having one column of twelve lines indicating the months of the year and a second column of twelve lines provided with a plurality of series of numbers, each series being the last two numbers of different years, and means co-acting with said table for presenting the first two numbers of a year and a table of numbers aligned in thirteen vertical columns, said table being 60 so arranged that when the number of the year on the second mentioned table is opposite any of the series of the numbers on the first mentioned table, seven columns thereof will be correctly positioned for indicating the days of the weeks in that particular month in that particular year.

10. A calendar of the character described comprising a tubular cap indicating the months of the year and a series of figures 65 indicating the last two figures of any year, and a member movable over said cap provided with a window adapted to disclose any two of said year figures, a series of numbers on said member indicating the days 70 of the month and two figures adjacent said window for co-acting with the numbers seen through said window.

11. A calendar of the character described comprising an inner member, a second member adapted to move over said inner member in two directions, and an outer member movable over said inner member, said outer member having three windows, one for indicating the month, one the year and one the days of the month, said second member having indications thereon presenting the days of the week for any month and the first two numbers of the year, and a window adjacent said year number, said inner member having indications thereon representing the months of the year with the number of days in the particular month along side and a series of numbers indicating the last two 85 numbers of a year, said last two numbers being adapted to be seen through the window of said second member, the particular position of the window determining the numbers disclosed, said numbers co-acting with the year number on said sleeve.

12. A calendar comprising a member having a line of legends indicating the months of the year and a second series of lines of legends indicating the last two numbers of different years, a second member adapted to 90 slide longitudinally and transversely over the first member, said second member having a window and a notch formed therein, said second member also having a table of numbers arranged so that any seven lines 95 thereof will indicate the days of the week of a given month, said second mentioned member being also provided with a year number having two figures arranged at the left of said window, an outer member mount- 100

ed to move in one direction over said second member, said outer member having a large window for disclosing seven lines of said table of numbers whereby the days of any 5 month may be seen, means indicating the days of the week arranged in a line on said outer member and acting as a heading to the number disclosed through the window in said outer member, a second window in said 10 outer member for disclosing one month of the year, said second window being adapted to be held in register with the notch in said second member, and a third window for disclosing the year number on said second 15 mentioned member and one of the year numbers on said first mentioned members.

13. In a calendar of the character described a sleeve, a window in the sleeve, two numbers indicating the first two numbers of 20 any year arranged adjacent said window, and a table of numbers on said sleeve arranged below said window, said table of numbers being so arranged that any seven vertical rows thereof will indicate a month.

14. A calendar of the character described comprising a tubular cap having a line of 25 designations thereon indicating the months of the year and a plurality of arbitrary series of numbers indicating the last two figures of any year, a rotatable and longitudinally movable sleeve fitting over said tubular cap, a series of numbers indicating the days 30 of the month positioned on said sleeve, and

numbers indicating the first two numbers of the year positioned on said sleeve, said sleeve 35 being formed with an opening adjacent said last mentioned numbers whereby when said opening is positioned over any of the series of arbitrary numbers on the tubular cap it will be read with the number adjacent the 40 opening on the sleeve for indicating the year.

15. In a calendar, a base member, an inner member movable transversely and longitudinally, an outer member movable transversely 45 simultaneously with the inner member, said members having indications, and means for disclosing simultaneously the year, the month and the days of the month for any month in any year within a period of seven 50 years by transverse motion of the outer member, and a longitudinal motion of the inner member.

16. In a calendar, a base member, an inner member movable transversely and longitudinally, an outer member movable transversely 55 simultaneously with the inner member, said members having indications, and means for disclosing simultaneously the year, the month and the days of the month arranged 60 in the order of the days of the week for any month in any year within a period of seven years by a transverse motion of the outer member and a longitudinal motion of the inner member.

PAUL S. HAUTON.
